United States Patent Office

Des. 206,893
Patented Feb. 7, 1967

206,893

SUGAR BOWL OR THE LIKE

Robert Y. Allen, Los Angeles, Melvin Shaw, Beverly Hills, and Evan K. Shaw, Rolling Hills, Calif., assignors to Metlox Manufacturing Co., Manhattan Beach, Calif., a corporation of California

Filed Mar. 1, 1966, Ser. No. 1,234

Term of patent 7 years

(Cl. D44—15)

FIG. 1 is a top view of a sugar bowl or the like, showing our new design;

FIG. 2 is a side view thereof; and

FIG. 3 is a bottom view thereof.

We claim:

The ornamental design for a sugar bowl or the like, substantially as shown.
